DESIGN FOR A DOLL BROOM

David Ruthenberg, Philadelphia, Pa.

Application August 27, 1945, Serial No. 121,661

Term of patent 3½ years

(Cl. D9—2)

To all whom it may concern:

Be it known that I, David Ruthenberg, a citizen of the United States, residing at Philadelphia, in the county of Philadelphia and State of Pennsylvania, have invented a new, original, and ornamental Design for a Doll Broom, of which the following is a specification, reference being had to the accompanying drawing, forming part thereof.

In the drawing:

Fig. 1 is a front view of a doll broom showing my new design.

Fig. 2 is a rear view of the doll broom shown in Fig. 1.

I claim:

The ornamental design for a doll broom, substantially as shown.

DAVID RUTHENBERG.
